SUCTION CLEANER

Charles H. Taylor, Springfield, Mass., assignor to
The Hoover Company, North Canton, Ohio, a
corporation of Ohio

Application May 9, 1938, Serial No. 206,739

3 Claims. (Cl. 15—16)

This invention relates to improvements in suction cleaners and more particularly to means whereby the nozzle of a suction cleaner is automatically maintained at the correct height above the surface of the floor covering to be cleaned regardless of its quality, texture or other characteristics.

Heretofore, it has been the standard practice to equip suction cleaners with some form of manually operated mechanism or device for adjusting the height of the nozzle for different grades and texture of carpet, it being well known that a predetermined uniform spacing of the nozzle above the carpet surface is essential to efficient operation and effective cleaning and further, that the nozzle should be raised or lowered to compensate for varying depths to which the wheels sink into carpets having different pile thickness. The chief objection to these manually operated adjusting devices is the fact that it is usually difficult for the operator to make the correct adjustment, not being familiar with the operating conditions. Moreover, operators frequently neglect to make any adjustment at all and as a consequence, the compensation for variations in carpet conditions is at best, uncertain and hazardous.

Therefore, the principal object of the invention is to incorporate a nozzle adjusting device into a suction cleaner that will automatically adjust itself to the particular kind or texture of carpet to be cleaned and thus eliminate the necessity of relying upon the operator to perform any act other than placing the cleaner upon the floor covering and operating it in the usual manner.

And a further object of the present invention is to provide a type of automatic nozzle height adjusting or regulating mechanism consisting of dual wheels vertically adjustable against spring tension to support the load, and so interconnected that the displacement of one wheel in contact with the carpet surface adjusts the other wheel, which in turn determines the correct height of the nozzle.

With the foregoing introductory matter, the invention will now be more fully disclosed in connection with the accompanying drawings in which:

Figure 1 is a general view in side elevation of a suction cleaner embodying the features of the invention and shown under operating conditions on a carpet of medium thickness.

Figure 2 is a fragmentary bottom plan view of the cleaner showing one set of adjustable wheels.

Figure 3 is a fragmentary view of the adjusting

mechanism set for operating on a relatively thick carpet and shown in side elevation as taken on line 3—3 of Figure 2.

Figure 4 is an enlarged detail view in vertical cross section taken on line 4—4 of Figure 1.

Figure 5 is a perspective view of the adjusting mechanism assembly.

Figure 6 is a perspective view of the bell crank lever forming a part of the adjusting mechanism.

Figure 7 is a view in side elevation of a modified nozzle height adjusting mechanism; and

Figure 8 is a bottom plan view of a cleaner showing the arrangement of the modified adjusting mechanism.

The suction cleaner herein disclosed may be considered as typical of any standard handle maneuvered cleaner adapted for household use and consisting generally of a casing 1 mounted on wheels and provided with a nozzle portion 2 extending transversely at its forward end. The casing 1 includes a fan chamber 3 in which is mounted a suction fan driven by a motor enclosed within a dome-like hood 4 on the casing. The nozzle portion of the casing consists primarily

of a downwardly opening nozzle chamber communicating with the fan chamber through a suitable inlet passage, said fan chamber communicating with a dirt bag 5 having detachable connection with an exhaust outlet connection at the rear end of the casing 1. A handle completes the cleaner assembly, the lower end portion in the form of a U-shaped bail 6 being pivotally connected to brackets 7, on opposite sides of the casing 1. Otherwise, the cleaner embodies the usual features of design which need not be described in detail.

The cleaner casing is supported upon wheels positioned near the front and rear ends thereof, the rear wheels 8, 8 being of standard size and dimensions and are journalled upon a suitable bracket 9 fixed to the cleaner casing. These wheels function in the usual manner to support the rear portion of the cleaner and will not be further considered.

The front wheels however, consist of two sets or pairs arranged side by side and substantially in axial alignment with each other, and are capable of adjusting themselves automatically under operating loads and in a degree determined by the characteristics of the carpet on which the cleaner is being operated.

Referring in greater detail to the front wheel arrangement, the corresponding wheels of each pair are located immediately to the rear of the outer end portions of the nozzle chamber and

within downwardly facing cavities extending along the sides of the casing 1. For convenience, the pairs of front wheels will be designated as the primary or supporting wheels 10, 10 and the secondary or auxiliary wheels 11, 11. The supporting wheels 10, 10 are located on the outside or adjacent the outer and side edges of the cleaner casing and may be further distinguished by the fact that they are substantially wider than the secondary or auxiliary wheels 11, 11 which are positioned just inwardly from and in close proximity to the supporting wheels. For the purpose of the present discussion the primary supporting wheels 10 may be assumed to be about three times the width of the narrow auxiliary wheels 11, 11 which have a width of say one-quarter ($\frac{1}{4}$) of an inch.

The supporting wheels 10, 10 are journalled at the forward ends of pivoted supporting brackets 12, 12 preferably assembled from sheet metal parts and pivotally supported, with corresponding brackets 13, 13 for the auxiliary wheels 11, 11, upon frames 14, 14 fixed to the underside of the cleaner casing. Each of the wheel supporting frames 14 (Figure 5) is stamped from sheet metal with ears 14a, 14a at each end which bear against depending bosses 15, 15 integral with the underside of the cleaner casing and to which the frame is fixed by means of screws to assume an inclined position at an angle of about 45°. The main portion of each frame 14 consists of a vertical central web 16 roughly triangular in shape with marginal segments on opposite sides thereof for supporting the several parts of the wheel assembly. Thus, at the upper end of the frame is a downwardly projecting integral arm 17 supporting between its lower end and that of the web 16, a bearing pin 18 on which bushing or collar 19 is mounted. This bushing 19, preferably flanged at either end, forms the bearing for the supporting wheel bracket 12, having the general shape of a bell crank lever (Figure 6) and consisting of a pair of L-shaped plates 20, 20, spaced apart with their horizontal arms 20a, 20a extending forwardly and supporting the ends of the journal pin 10a for the front wheel 10. The other and vertical arms 20b, 20b of the plates 20, 20 are bent at right angles just above the bushing 19 and laterally inward and again bent upwardly at right angles and into contact with each other and finally joined together into a single upright lever arm offset some distance inwardly from the plane of the wheel 10 supported by the main portion of the bracket with the extremity of one of the upright arms fashioned into a tapered or wedge-shaped cam 21 extending rearwardly with a slight inclination in an upward direction, the under edge of this cam being the active cam surface, and inclined to the vertical at an angle of approximately 45°.

To complete the pivotal mounting of each supporting wheel bracket 12 on the supporting frame 14 a torsion spring 22 consisting of approximately three turns is coiled about the bushing 19, one end of the torsion spring being hooked about the rear edge of the wheel supporting bracket 12 immediately above the bearing 19 (Figure 4) and the other extremity of the spring being caught over a finger 23 formed integral with the outlying arm 17 of the frame 14 (Figure 5), the torsion spring thus acting to exert continuous pressure on the wheel supporting bracket 12 in a direction to yieldingly resist the load placed upon the supporting wheels 10, 10 when the cleaner is in operation. In other words, each torsion spring 22

5 tends to rotate its wheel supporting bracket 12 in a clockwise direction as viewed in Figure 1. However, it is to be noted at this point that the tension exerted by the torsion springs 22 is calculated to be considerably less than that necessary to overcome the operating load on the front wheels, although ample to support the front portion of the cleaner under static load conditions, that is, when the cleaner is not operating under suction load, as will presently be explained in greater detail.

In the meantime, it may be observed that the rotative movement of the wheel carrying brackets 12, 12 on their bearings 19, 19 is transmitted from each associated auxiliary wheel carrying brackets 13 through the medium of a Z-shaped cam lever 24 pivotally mounted on a bearing pin 25 carried on the frame 14 directly to the rear of the pivotal axis of the wheel supporting bracket 12 and projecting inwardly beyond the central web 16 of the frame.

Leaving the Z-shaped cam lever 24 for the moment, the supporting bracket 13 for each of the auxiliary wheels 11 is located just inwardly from the primary wheel supporting bracket 12 and consists of an elongated U-shaped lever formed of sheet metal and having bearing at its rear end upon a transverse pivot pin 26 supported at the rear end of the frame 14. This wheel supporting lever 13 extends in a horizontal direction and throughout its forward end portion it is bifurcated to receive the narrow auxiliary or pilot wheel 11. As clearly shown in Figures 2 and 4, each lever 13 has an upwardly opening U-shaped portion 27 with a section of its outermost side wall cut away as at 27a to allow the pivot pin 25 to project into the open U-shaped recess and to bring the Z-shaped cam lever 24, previously identified, into position immediately above the lever.

Now, the cam lever 24 carries at its lower end and just forwardly of its pivotal support on the pin 25, a roller 28 which bears upon a narrow metal plate or strip 29 extending along the bottom of the U-shaped recess intermediate the ends of each lever 13, said strip being suitably anchored as by welding at its rearmost end. Immediately beneath the forward and free end of the strip 29 is an adjusting screw 30 threaded through the bottom web of the lever 13 and bearing at its upper end against the underside of the plate 30 which, being somewhat resilient, is adapted to be raised or lowered thereby to impart a limited adjustable rotative movement to the Z-shaped cam lever 24 by contact with the roller 28. The adjusting screw 30 is provided with a lock nut 31 to hold the same in any position of adjustment. The purpose of this adjusting screw will be brought out in connection with the discussion of the operation of the nozzle adjusting mechanism.

60 As thus far described, each Z-shaped cam lever 24 pivots about its bearing pin 25, the rocking movement of the lever 13 being transmitted to said cam lever through contact with its roller 28. And finally, this movement is transmitted from the cam lever 24 to the primary wheel supporting bracket 12 through a roller 32 journalled at the upper end of the cam lever 24 and engaging the cam 21 of the wheel supporting bracket. And finally, to complete the Z-formation of the cam lever 24, a short arm 24a projects rearwardly from its upper end with its extremity bent at right angles and folded back upon itself to form an abutment for one end of a compression spring 33. The opposite end of

said spring is supported at the end of a tension adjusting screw 34 supported by an ear 35 formed integral with the supporting bracket 14 and extending transversely from the rear edge of the central web 16 thereof (Figure 5). A lock nut 36 is applied to the outer portion of the adjusting screw 34 which also has its end slotted transversely so that a screw driver may be applied for rotating to either increase or decrease the pressure exerted by the coil spring 33 on the 10 Z-shaped cam lever 24.

This completes the description of each adjustable front wheel assembly and, bearing in mind that the same is duplicated on each side of the cleaner, the adjusting action may be summarized as follows: The outermost or wide supporting wheels 10, 10 are adjusted upwardly and downwardly by the rocking movement of their supporting brackets 12, 12 limited however to the movement thereto through the contact of the cam rollers 32, 32 with the cams 21, 21 which in turn depends upon the degree of rocking or oscillating movement imparted to the Z-shaped cam levers 24, 24 by the movement of the supporting brackets 13, 13 carrying the innermost or narrow auxiliary wheels 11, 11. It follows therefore that if the auxiliary wheels are permitted to be depressed below their normal horizontal position, this movement allows the cam levers 24, 24 to rock forwardly under the tension of the springs 33, 33 and transmit a rocking movement to the main wheel supporting brackets 12, 12, in the same direction, that is, downwardly in a clockwise direction, with the result that the primary load supporting wheels 10, 10 are depressed and the forward end of the cleaner body is elevated to raise the nozzle accordingly.

And in this connection, it is important to note that the auxiliary wheels 11, 11 are journaled at the ends of lever arms considerably longer than the lever arms 20a of the brackets 12, 12 carrying the supporting wheels 10, 10, and hence, the force exerted by the springs acting through the former is greater than that acting through the latter with the result that the auxiliary wheels 11, 11 are depressed with greater force and therefore assume a greater part of the load, say, from 75 to 80% with the main supporting wheels 10, 10 carrying the remaining 25% or 20% of the load. However, this applies only to the static load, so that upon starting the cleaner in operation, the suction load becomes effective and immediately there is a tendency for the wheels to sink or penetrate to a greater depth into the carpet nap. Now, since the auxiliary wheels 11, 11 are capable of carrying the greater load before yielding to the added weight imposed upon them, it follows that they will sink into the carpet nap to the maximum depth permitted by the thickness and texture of the carpet pile and when that depth is reached, the auxiliary wheels will move toward the cleaner casting and the movement of the supporting levers 13, 13 will be transmitted to the brackets 12, 12 carrying the main supporting wheels 10, 10, through the cam levers 24, 24. And since the main supporting wheels 10, 10 are intended primarily to carry only the suction load and to ride upon the carpet nap with comparatively little penetration, due to their relatively wider tread surfaces, their vertical position determines the ultimate height of the nozzle above the carpet surface. In short, the wide wheels 10, 10 are displaced vertically and move upwardly or downwardly with the auxiliary wheels 11, 11 but 75 in a reduced amount proportional to the rela-

tive lengths of their respective lever arms. Thus it will be seen that the greater the depth of the carpet pile, the greater the penetration of the auxiliary wheels 11, 11 and the correspondingly greater vertical adjustment of the supporting wheels 10, 10 in a direction to raise or lower the nozzle and thus maintain its uniform height regardless of the particular characteristics of the carpet being cleaned.

However, before starting the cleaner in operation, the adjusting mechanism has to be properly set by manipulating either the bottom adjusting screw 30 or the compression spring adjusting stem 34, or both. This setting would ordinarily be made before the cleaner leaves the factory and based on a predetermined nozzle height of say, $\frac{1}{8}$ of an inch as measured between the front lip of the nozzle mouth and the surface of the carpet nap. And this setting once made would ordinarily be permanent whereupon the cleaner should respond to variations in quality and texture of the ordinary range of carpets to be cleaned.

Thus, the characteristic features of the adjusting mechanism herein disclosed is the utilization of pairs of adjustable wheels, one pair being relatively more responsive or susceptible to variations in the quality and texture of the carpet than the other, and acting to adjust the position of the latter which in turn determines the height of the nozzle. Needless to say, the same principles may be incorporated in other and even simpler forms, one of which has been disclosed in Figures 7 and 8.

In the modified disclosure of the adjusting mechanism, the wheels constituting each set are located at the forward end of the cleaner as before, but are positioned one behind the other rather than side by side. Moreover, foremost wheels 40, 40 are relatively wider and constitute the primary wheels, while the rear wheels 41, 41 are the auxiliary wheels. Each of the primary wheels 40 is journaled at the lower end of a short lever 42 pivotally mounted intermediate its ends at the lower extremity of a vertical arm 43 formed integral with a bracket 44 suitably fastened to the underside of the cleaner casting. Each of the auxiliary wheels 41 is similarly journaled at the end of a longer lever 45 also having pivotal connection with the arm 43 just above the pivot point of the lever 42 and extending downwardly and rearwardly therefrom. Bearing against the levers 42 and 45 adjacent their outer ends are compression springs 46 and 47 respectively with their other ends seating against abutments formed by the bracket 44.

The rearmost wheels 41, 41 correspond to the auxiliary wheels 11, 11 of the previous disclosure and therefore, the compression springs 47, 47 are heavy enough to counterbalance the greater part of the static load, while the springs 46 are somewhat lighter and act primarily to resist the displacement of the front wheels under load. And finally, the levers 42 and 45 are interconnected by a simple cam arrangement consisting of a pin 48 projecting from the face of the longer lever 45 and bearing against a cam finger 42a at the upper end of the lever 42.

Thus, as the rear wheels 41, 41 sink into the carpet nap under operating load, the depth of penetration is reflected in the slight swinging movement of their supporting levers 45, which is transmitted to the levers 42, shifting them in a direction to depress the forward wheels and thus act in the same manner as the wheels 10,

10 in the previous disclosure to raise or lower the nozzle and thus compensate for the variation in the thickness and texture of the carpet.

Having set forth a complete disclosure of the invention,

I claim:

1. A suction cleaner comprising a body having a nozzle at its forward end and pairs of front and rear supporting wheels, said front supporting wheels journaled on brackets pivotally mounted on said body, a pair of auxiliary wheels associated with said front supporting wheels and arranged substantially in axial alignment therewith, brackets pivotally mounted on said body and carrying said auxiliary wheels, springs acting on said auxiliary wheel supporting brackets to counterbalance a predetermined portion of the weight of the cleaner body, a lever shiftable with the displacement of each of said auxiliary supporting brackets caused by the depression of said auxiliary wheels into the carpet surface under the operating load of said cleaner, and a cam member on each of said front wheel supporting brackets and contacting said lever to effect a corresponding vertical displacement of said primary supporting wheels and adjust automatically the height of the nozzle to the depth of penetration of said auxiliary wheels into the surface of the carpet to be cleaned.

2. A suction cleaner comprising a body having a nozzle at its forward end and pairs of front and rear supporting wheels, the front wheels consisting of pairs of associated primary and auxiliary wheels having relatively wide and narrow tread surfaces respectively, and arranged side by side in substantially axial alignment, brackets pivotally mounted on said body and having horizontally extending arms carrying said wheels at their ends, spring-pressed levers act-

ing on said auxiliary wheel supporting brackets to oppose yieldingly to the displacement of said auxiliary wheels under the weight of the cleaner body, said primary wheel supporting bracket having a cam member bearing on said spring-pressed lever, whereby the increased depth of penetration of said auxiliary wheels under full operating load condition of said cleaner by virtue of their decreased width, effects a proportional displacement of said primary supporting wheel to adjust automatically the height of said nozzle to the particular carpet surface being cleaned.

3. A suction cleaner comprising a body having a nozzle at its forward end and pairs of front and rear supporting wheels, the front wheels consisting of pairs of associated primary and auxiliary wheels having relatively wide and narrow tread surfaces respectively, frames mounted on said body, pairs of brackets pivotally mounted side by side on said frames and having horizontally extending arms carrying said wheels at their forward ends, spring-pressed levers carried by said frames and acting on said auxiliary wheel supporting brackets to oppose yieldingly to the displacement of said auxiliary wheels under the weight of the cleaner body, said primary wheel supporting brackets having cam members bearing on said spring-pressed levers, whereby the increased depth of penetration of said auxiliary wheels under full operating load condition of said cleaner by virtue of their decreased width and the increased length of the lever arms of their supporting brackets, effects a proportional displacement of said primary supporting wheel to adjust automatically the height of said nozzle to the particular carpet surface being cleaned.

CHARLES H. TAYLOR.
